UNITED STATES PATENT OFFICE.

WILLIAM J. COCKLIN, OF RISING CITY, NEBRASKA.

GRAIN-DOOR.

No. 818,816.

Specification of Letters Patent.

Patented April 24, 1906.

Application filed July 31, 1905. Serial No. 272,041.

To all whom it may concern:

Be it known that I, WILLIAM J. COCKLIN, a citizen of the United States, and a resident of Rising City, in the county of Butler and State of Nebraska, have invented a new and Improved Grain-Door, of which the following is a full, clear, and exact description.

The invention relates to a door for freight-cars of the type known as "box-cars," by which door the cars may be rendered sufficiently tight to permit loading grain in bulk. The object of the invention is to simplify the construction of the door, render it stronger or more durable, and permit it to be readily folded, so that it will not interfere with using the car for other freight.

The invention resides in certain special features of construction and arrangement of parts, as will be fully set forth hereinafter and particularly pointed out in the claims.

Reference is had to the accompanying drawings, which illustrate as an example the preferred embodiment of my invention, in which drawings—

Figure 1 is an outer side elevation of the door closed. Fig. 2 is a cross-section on the line 2 2 of Fig. 1 and showing by dotted lines the folded position of the door. Fig. 3 is an inner side elevation of the door closed, parts being in section on the line 3 3 of Fig. 2. Fig. 4 is a section on the line 4 4 of Fig. 1. Fig. 5 is a section on the line 5 5 of Fig. 1. Fig. 6 is a detail of one of the dogs for holding the door closed, and Fig. 7 is a sectional view showing a modification.

Referring to Figs. 1 to 6, 10 indicates the upper section of the door, and 11 the lower section. These are provided with butt-straps 12, connected by a horizontal rod 14, whereby hingedly to join the sections of the door. The lower section 11 is provided at its edges with metallic binding-plates 16, which abut against the inner face of the frame 19 of the door, and cleats or battens 15, secured to the inner sides thereof. These cleats carry stop-plates 20, which overlap the side edges of the door-section 11 and prevent inward movement thereof. The edges of the plates 16 are respectively fastened to the side faces of the door, and at the outer side of the door intermediate portions of the binding-plates 16 stand away from the door, forming cleats or beads, and have latches 17 pivoted thereto, which are arranged to engage in cavities 18, formed in the door-frame. The binding-

plates 16 are fastened to the door-sections by rivets or other suitable means. By this means a tight connection is effected between the lower section 11 and the frame of the door, and by releasing the latches 17 the said section may be swung outward on the rod 14 and raised against the upper section. 21 indicates a hook in the outer side of the section 10 for holding the lower section raised. At its lower edge the section 11 has a metallic binding-plate 22.

The upper section 10 has a binding-plate 23 at each side edge, which plates, as shown best in Fig. 4, have their edge portions engaged with and fastened by rivets or other desired means with the respective faces of the door-section. Intermediate portions of these plates 23 stand or project outward from the outer face of the door, producing beads which are located inward of the extreme side edges of the door to form rabbets 23^a. Each door-section 10 engages the inner side of the door-frame, while the said bead abuts against the inner face of the frame, the rabbets 23^a of the binding-plates receiving the vertical inner edge of said frame. Latches 24 are pivoted to the beads of the plates 23 and are adapted to engage in the cavities 25 in the frame of the door, the same as the latches 17 before described. The hinge-butts 12 before described are fastened, respectively, to the adjacent edges of the upper and lower edge sections, while the hinge-butts 12^a are fastened, respectively, to the beads of the binding-plates 16 and 23, as shown in Fig. 1. In addition to the function above named, the beads which are formed on the binding-plates 16 and 23 serve also as strengthening posts or columns for the door-sections. These strengthening members extending along the vertical edges of the door lend strength thereto and greatly increase the durability of the parts. On this lower edge the upper section 10 of the door is provided with a binding-plate 33. The upper edge section is hung by rods 26, which have their lower ends arranged to turn in bearings 27, attached to the inner side of the section 10, and their upper ends in bearings 28, attached to the joist 29 over the door, as Fig. 3 shows, the ends of the rods being turned to form journals rocking in the bearings, so that the rods may swing with the door around the center of the bearing 28. These rods permit the door to assume the active position shown in the drawings and to swing upward.

to the folded position shown by dotted lines in Fig. 2.

Attached to the upper end of the section 10 is a hook 30, which is adapted to engage a sling 31, projecting down from the center roof joist of the car, as shown in Fig. 2. This holds the door raised at this point. The joist 29 is provided with two socket-pieces 32, having notches 32^a in their upper ends, the socket-pieces receiving the headed shanks 33 of hangers 34, which are positioned to engage the lower edge of the section 10 when folded and to sustain the same, as shown by dotted lines in Fig. 2. The hangers when not in use may be folded sidewise, as shown in Fig. 3, the notches 32^a of the socket-piece 32 holding the hangers in either active or inactive position.

In the use of the door the parts are arranged as shown by full lines to close the doorway and keep the grain in the car. The car is provided with the usual sliding door, which covers the doorway and grain-door, as will be understood from the prior art. To unload the grain the lower section 11 should be swung up against the section 10 and temporarily fastened by the hook 21, thus allowing part of the grain to flow out the doorway, the remainder being shoveled out. To fold the door when using the car for other freight than grain, the section 11 should be swung back on section 10 and fastened by the hook 21. Then both sections should be thrown up, as shown by broken lines in Fig. 2, and held by the hook 30 and hangers 34.

It will be seen that the device when in use forms a thoroughly tight door, preventing the escape of any of the grain, and when it is desired to use the car for other purposes the door may be folded into inactive position and effectually put out of the way.

The modification shown in Fig. 7 contemplates the use of a door formed in a single section 36, this section being provided with an opening 36^a in its lower portion which receives a smaller door section or closure 37. The closure 37 is connected to the section 36 of the door by a hinge 38 at the outer edge of the closure 37, and it is provided with a suitable latch for holding it securely in closed position. Said closure 37 takes the place of the hinged lower section hereinbefore described.

My improved door does not need to be nailed, and the iron bindings prevent persons

from driving nails, thus prolonging the life of the doors.

Having thus described the preferred form of my invention, what I claim as new, and desire to secure by Letters Patent, is—

1. In a grain-door, the combination with a car having a door-opening therein, of upper and lower door-sections, means for hingedly connecting them, means for supporting the door-sections, a metallic binding-plate running along the vertical edges of the upper door-section, said binding-plate having its edges fastened respectively to the side faces of the door-section, and an intermediate portion projecting outward from the face of the door-section to form a strengthening bead or column, the door-section being arranged to bear against the inner side of the door-frame, and the said bead of the binding-plate abutting against the inner face of the door-frame and forming a rabbet receiving the inner vertical edge of said frame, and a metallic binding-plate running along each vertical edge of the lower door-section, said plate having its edges respectively fastened to the sides of the door, the plate having intermediate its edges an outwardly-projecting strengthening bead or column abutting against the inner face of the door-frame.

2. A grain-door having a metallic binding-plate running along the edge thereof, said plate having its edges respectively fastened to the sides of the door, the plate having intermediate its edges an outwardly-projecting strengthening bead or column.

3. A grain-door having a metallic binding-plate running along its edge, said binding-plate having its edges fastened respectively to the side faces of the door, and an intermediate portion projecting outward from the face of the door to form a strengthening bead or column, the door being arranged to bear against one side of the door-frame, and the said strengthening bead or column abutting against the inner face of the door-frame and forming a rabbet receiving the edge of the door-frame.

In testimony whereof I have signed my name to this specification in the presence of two subscribing witnesses.

WILLIAM J. COCKLIN.
